WILHELM ULRICH, OF JENA, GERMANY.

MERCURY VAPOR LAMP.

Application filed March 23, 1927, Serial No. 177,710, and in Germany March 29, 1926.

For igniting mercury vapor lamps they are tilted in such a manner that the mercury flows from one pole, for instance out of the anode body filled with mercury, through the lighting tube towards the other pole to the cathode, so that a conductive connection between the two poles is only established through the mass of mercury. It has, however, been found that in most cases ignition 5 does not take place immediately and that it is necessary to tilt the lamp several times, before the arc is established in the tube, and that owing to the considerable mass of mercury which flows in the tube when this is 10 done, the arc is apt to be ruptured again and extinguished on the lamp being tilted back again into the burning position, through the mass of mercury flooding back again, so that it is necessary to tilt the lamp again for causing ignition. 15

These drawbacks are overcome according to the present invention by the mercury not being conveyed from one hole to another in a full stream occupying a large part of the 20 tube, for causing ignition, but being conveyed to the other pole only in one or more fine streams.

A lamp constructed in accordance with the present invention is shown in the accompanying drawing, in which a mercury vapor lamp 25 is represented, having two anode bodies partially filled with mercury and one cathode body filled with mercury.

Fig. 1 being a plan view of the lamp,

Fig. 2 a side elevation of the same,

Fig. 3 a view of the single cathode end with lamp in the tilted position,

Fig. 4 a view of the lamp when burning, and

Fig. 5 a partial longitudinal section 40 through a second constructional form whose omitted part corresponds with the right hand part of Figure 4.

According to the invention an arrangement is provided, by which for igniting the lamp the mercury is conveyed from one pole, in the example shown the mercury out of the anode body *a*, in a fine stream to the other pole, in the example shown to the mercury 50 in the cathode body *b*.

For this purpose in or on the illuminating tube *c* in a known manner conducting means are provided, for instance gutters or fine tubes *d*, which extend along the greater part 55 of the illuminating tube *c*. Preferably in

the vicinity of the anode bodies *a* or in the same a wall *e* is provided which partly shuts off the illuminating tube *c* or the connection between the latter and the anode body and from which the fine tubes *d* start. By this means there will be a certain damming up 60 of the mercury level at the starting point of the fine tubes, as is indicated at *f*, thus ensuring that, on the lamp being tilted, there will be a prolonged flow of mercury through the 65 fine tubes *d*.

The fine tubes are so arranged that, when the lamp is burning, they lie outside the arc which after a short period of time, more particularly in the case of so-called high pressure lamps, separates from the wall of the illuminating tube and is constricted to a luminous band *A* of relatively small cross-sectional area, as is indicated in Figure 4. For this purpose the conducting means, for 70 instance the fine tubes *d*, are placed as near as possible to the wall of the illuminating tube, in the example shown the lower wall of the said tube, their ends being in this case slightly bent upwards and inwards, as indicated at *d'*, for ensuring, on the lamp being tilted, that the jets of mercury emerging 75 at *d'* will be directed to the other pole, in the example shown the mercury of the cathode body. By this arrangement an arcuate 80 jet of mercury is produced, which, even when mercury gradually accumulates in the neighbourhood of the cathode, still makes ignition possible. In Fig. 3 *g* represents the jet of mercury emerging from the fine tube *d*. 85

On the lamp being tilted for igniting it, the fine jets *g* of mercury emerging from the fine tubes *d* immediately establish the conductive connection and in a relatively short space of time the interior space of the lamp 90 will have become conductive owing to ionization or the like, so that the arc is established and the lamp can be tilted back into the burning position. As only a relatively small quantity of mercury passes out through the fine 95 tubes and ignition takes place remarkably rapidly, there will not be such a backward rush of mercury, on the lamp being tilted back into the burning position, that the arc which has been established will be ruptured 100 again and extinguished. Owing to the fact that the conductive means for the fine flow of mercury for ignition purposes do not extend right up to the other pole and are so arranged that they lie outside the range of the 105 110

arc, there is no danger of these parts being in any way changed, for instance by being fused, owing to the high temperature of the arc.

5 This arrangement is of course just as applicable, when instead of a mercury cathode a metallic cathode is used, on to which the fine jets of mercury are conveyed. The arrangement may of course also be such that the conducting means for the fine jets of mercury start from the cathode and lead to the anode and also such that they lie outside the illuminating tube instead of within it, as in the example shown, only opening into the interior 10 of the illuminating tube in the vicinity of the other pole.

15 In the constructional form shown in Fig. 5, the wall which dams back the mercury and forces it to enter the conducting means, for 20 instance the fine tube *d* is approximately horizontal, as shown at *h*. This constructional form has the special advantage that, when the lamp is returned from the tilted into the burning position, the mercury contained in 25 the illuminating tube *c* will flow back to the last drop into the anode body *a*.

What I claim is:

1. A mercury vapor lamp comprising in combination an illuminating tube capable of 30 being tilted, anode and cathode bodies on the said illuminating tube, constituting the poles, at least one container in the said anode and cathode bodies for containing mercury, fine tubes extending longitudinally of the 35 said illuminating tube from the pole vessel containing the mercury to the vicinity of the other pole, and means at the junction of the fine tubes and the pole vessel containing the mercury for obstructing the flow of the mer-

cury, on the lamp being tilted, and allowing 40 it only to enter the fine tubes.

2. A mercury vapor lamp comprising in combination an illuminating tube capable of being tilted, anode and cathode bodies on the said illuminating tube, constituting the poles, 45 at least one container in the said anode and cathode bodies for containing mercury, fine tubes extending longitudinally of the said illuminating tube from the pole vessel containing the mercury to the vicinity of the 50 other pole, obstructing walls at the junction of the fine tubes and the pole vessel containing the mercury and an opening in each wall for the connection of the fine tubes for the purpose of allowing the mercury, when the 55 lamp is tilted only to enter the fine tubes.

3. A mercury vapor lamp comprising in combination an illuminating tube capable of being tilted, anode and cathode bodies on the said illuminating tube, constituting the poles, 60 at least one container in the said anode and cathode bodies for containing mercury, fine tubes positioned in the illuminating tube at one side of the same and extending from the pole vessel containing the mercury to the 65 vicinity of the other pole and having this end bent for enabling an arcuate jet of mercury to be formed and for ensuring a good contact with the last named pole, obstructing walls at the junction of the fine tubes and the pole 70 vessel containing the mercury and an opening in each wall for the connection of the fine tubes for the purpose of allowing the mercury, when the lamp is tilted only to enter the 75 fine tubes.

In testimony whereof I have signed my name to this specification.

WILHELM ULRICH.
